Atlys.

United States Patent Office.

G. A. HEIN. OF WATERFORD, PENNSYLVANIA.

Letters Patent No. 78,087, dated May 19, 1868.

IMPROVED WATER-SPOUT FASTENING.

The Schedule referred to in these Letters Patent and making part of the same.

TO ALL WHOM IT MAY CONCERN:

Be it known that I, G. A. HEIN, of Waterford, in the county of Erie, and State of Pennsylvania, have invented a new and improved Water-Conductor Fastening; and I do hereby declare that the following is a full, clear, and exact description thereof, which will enable those skilled in the art to make and use the same, reference being had to the accompanying drawings, forming part of this specification.

The object of this invention is to provide a fastening for the water-conductors of buildings, which, while it presents a neat and workmanlike appearance, and is durable, and not likely to get out of order, shall allow the conductor to be attached to or removed from the same without removing the fastening.

And the invention consists in attaching the conductor to the building by a jointed clasp, having a screw or spike attached thereto, as will be hereinafter described.

Figure 1 is a longitudinal section of a conductor attached to the side of a building with my improved fastening.

Figure 2 is a cross-section of the fastening and conductor through the line *z z*.

Similar letters of reference indicate corresponding parts.

A represents the outside wall of a building.

B is the conductor attached thereto, for conveying water from the eaves-spout.

C is the fastening. This fastening is made in the form of two semicircles or other equivalent form, of sheet or band metal, of suitable size.

The two parts are permanently jointed or hinged together at *d*, and the other connection at *e* is in the hinge-form, but the pin *f*, by which the two parts are joined, is removable, as seen more plainly in fig. 1.

The two parts of the fastening may be designated by the letters F G.

To the part G there is a screw or spike, H, attached, as seen in the drawing, which is screwed or driven into the building, as seen in dotted lines in fig. 1.

When the connection with the building is thus made, the conductor-pipe is placed in the circle, or in contact with G, and the part F is clasped over or around it, and secured to G by the pin *f*, as seen in fig. 1.

To keep the conductor in place, or to prevent its slipping down from its own weight, there are little brackets, *i*, forming shoulders, attached to it, which rest upon the clasp, as seen in the drawing.

The arrangement and application are so plainly shown in the drawing, that further description is deemed unnecessary.

Having thus described my invention, I claim as new, and desire to secure by Letters Patent—

The conductor-fastening C, composed of two or more circular parts jointed together, and fastened to each other and to the building, substantially as herein shown and described.

G. A. HEIN.
